UNITED STATES PATENT OFFICE.

WILLIAM STEPHENSON, OF MORRIS, CANADA.

SEED-DRILL-DISK SHOE.

SPECIFICATION forming part of Letters Patent No. 603,863, dated May 10, 1898.

Application filed July 10, 1897. Serial No. 644,055. (No model.)

To all whom it may concern:

Be it known that I, WILLIAM STEPHENSON, a citizen of the Dominion of Canada, residing at Morris, in the county of Provencher, in the 5 Province of Manitoba, Canada, have invented certain new and useful Improvements in Seed-Drill-Disk Shoes; and I do hereby declare that the following is a full, clear, and exact description of the construction and operation of the same.

The invention relates to further improvements on seed-drill-disk shoes such as are described in my previous application, Serial No. 543,467, filed May 28, 1895, and in Letters 15 Patent No. 588,027, granted to me on the 10th day of August, 1897.

The objects of my present invention are to provide, first, the grain-spout so constructed as to be better protected from mud and water 20 and not so liable to be clogged up; second, the journals are also better protected from dust, &c., thus preserving the lubricating-oil and conducting it out on the inside of each disk and central scraper, keeping the parts always lubricated, prevents mud from sticking 25 to the inside of the disks, and, further, prevents rusting of the same; third, the oil-channel is in the rear side of the grain-spout, and consequently it is easier to get at it and 30 more convenient every way to the operator; fourth, a double adjustable central scraper is constructed and placed between the disks for the purpose of keeping the inner surfaces of the disks clean and preventing mud from 35 clogging up the spout portion during the operation of the machine, and, fifth, two outside self-acting side scrapers, having two motions, being pivoted to levers, and the latter pivoted to the said scrapers, are provided, and the 40 outer ends of the levers are pressed apart to cause the scrapers to slightly impinge on the outer edges of the disks and keep them clear of mud. To the accomplishment of these objects my invention consists in the parts and 45 several combinations of parts hereinafter described and claimed.

In the accompanying drawings, Figure 1 represents a side elevation of a grain-drill shoe embodying my invention. Fig. 2 is an 50 end view of the same. Fig. 3 represents a side view of a casting embracing a combination of grain-spout, draw-bar connection,

shield, hollow standard, oil-chamber, and grain-guide all cast in one piece. Fig. 4 represents an inside view of one of the scrapers 55 detached pivoted to its lever. Fig. 5 represents a top view of one of the scraper-levers detached. Fig. 6 represents a rear view of the lower main central scraper. Fig. 7 is a similar view of the adjustable top-portion part 60 of the scraper. Fig. 8 is an edge view of the upper and lower parts of the double scraper. Fig. 9 is a longitudinal section of the bottom of the oil-reservoir and axles.

In the drawings, A represents the casting, 65 combining the grain-spout a, the draw-bar connection b, the shield c, the oil-conduit d, the grain-guide e, the hollow tapering axles f f, the oil-reservoir g, side lugs h h, and rear lugs i i, and 3, and these parts will collectively hereinafter be indicated by the casting A, and it will be observed that in constructing the said casting the hollow tapering axles are cone-shaped and chill-hardened, the outside being quite smooth, and afford an excellent bearing for the disks, which are designated by the letter B. They are about twelve inches in diameter and made of thin 70 spring-steel plate, the outer edges of which are beveled about five-eighths of an inch inward from the outer periphery of the edge, as shown at Fig. 2, and have riveted to their outer centers a slightly-beveled hub C, and are each placed on the corresponding tapering axles f f of the casting A and held thereon by means of a bolt j, passing through a washer k at each end of the axles f and secured at the threaded end by a nut l, thus securing the disks B to the casting A, as shown. It will be seen that the outer ends 75 of the hub C are screw-threaded and are protected from mud and dust by means of conical-shaped caps m, which are hollow and threaded on the inside and made to screw on the corresponding threaded hubs C C, they 80 having also crossed notches n on their outer end, in which to insert a large screw-driver or suitable flat rod to tighten or release them.

It will be observed that my method of oiling the axles f f and also the inside of the 85 disks B B at the same time is peculiar and highly efficient and may be described as follows:

The oil-conduit is in rear of the grain-

spout, and the oil is poured in the top orifice of the conduit *d*. Thence it passes down into the oil-reservoir *g* in the interior of the hollow axles *ff*. It then exudes slowly through 5 notches *o*, made in the extreme outer end of the said axles *ff*, and thence finds its way up and around the axles between them and the hub, thoroughly lubricating the parts so necessary for their proper operation. Thence the oil 10 exudes onto the inside of the disks and prevents them from retaining mud, dust, &c., besides preventing them from rusting. I may also say here that when the oil flows through the oil-openings *o* in the ends of the axles a portion of it forces its way behind the washers *k* into the inner cavity of the screw-caps 15 *mm*, which forms a kind of secondary oil-reservoir *p*, and their rotary motion brings the oil always to the top of the axles, which 20 materially assists in keeping the parts always thoroughly lubricated.

In practice it will be found best after the oil is deposited in the oil-conduit and oil-chamber to insert a piece of cotton-waste into 25 the oil-conduit *d*, the lower screw of the central scraper projecting into the oil-conduit far enough to prevent the waste from going farther down into it, and the entrance to the said conduit is tightly corked.

30 The different scrapers may be described as follows:

The side scrapers consist of two irregular-shaped plates *q*, provided with lugs *r* on their rear side, to each of which is pivoted a lever 35 *s*, the latter also being pivoted to lugs *h*, having a steel pin *a'* affixed thereto for that purpose, the lever being secured by a cotter-pin *b'*, passed through the said pin *a'*. The outer ends of said levers are bent inward, and a 40 spiral spring *t* of the requisite degree of strength is slipped over the said lever ends to press them apart and thus cause the said side scrapers *q* to impinge on the outer side of the disks *B*, as shown at Fig. 2, and clean 45 them. The tension of the said spring *t* can be adjusted by means of small holes *u* in the bent part of one of the levers *s*, when the spring can be compressed and a pin *v* placed in any of the said holes *u* to increase or 50 diminish the tension-pressure of the scrapers *q* on the outside of the disk *B*, according to the nature of the soil. By this means the outside cutting edge of each disk is kept clear 55 of soil. The inner face of each of the said disks is kept clean by means of two adjustable central scrapers *w* and *w'*. The larger and lower scraper *w* is tapered to correspond to the slanting position of the disks *B*, as shown at Fig. 2 and detached at Fig. 6, having a 60 longitudinal slot *x*, over which a washer *z* is placed for a screw-bolt *y* to pass through and made to screw into the lug *i* on the rear of the casting *A*, the upper part of the said scraper resting against the lug *3*. Thus it 65 will be seen that by means of the slot *x* the scraper can be adjusted vertically to suit the

angle of the two disks *B* to keep their central portion clear of mud when in operation. It will be seen that the edges of the disks *B* are beveled inward about five-eighths of an 70 inch from the outer edge, and the short upper scraper *w'* is beveled from its center downward to correspond to the bevel of the disks, as shown at Figs. 2 and 7. It has also a slotted opening *x'*, through which a capped screw 75 *y'* is made to pass to screw into the lug *i'*, cast on the rear of the grain-spout casting *A*, a washer being placed between the screw-head and the scraper, and thus the said upper scraper *w'* can be adjusted so that the wear of 80 the same can be taken up to correspond to the bevel of the disks. In their normal position the top scraper *w'* will overlap the lower one *w* about one-eighth of an inch, the result of these two central scrapers being to keep the 85 inside surfaces of the disks always clean as they revolve past the scrapers when in operation.

I do not in this application claim the combination of a grain-spout, revolving disks 90 mounted upon the opposite sides thereof, and a tapering scraper adjustably mounted upon the grain-spout and between the disks, the said disks revolving in intersecting planes, whereby the adjustment of the scraper vertically regulates the bearing of the scraper on the inner faces of both of the said disks, as such matter is described in my hereinbefore-mentioned application, Serial No. 543,467; but

100 What I do claim is—

1. A casting for seed-drills, having an axle on each side thereof, a grain-guide in front of the axles, and a shield in front of the guide, the whole being cast integral and being provided with a grain-spout between the axles and the grain-guide, substantially as described.

2. A casting for seed-drills, having a hollow axle on each side thereof, and a grain-guide and a draw-bar connection in front of the axles, and provided with a grain-spout in front of the axles and an oil-conduit, in the rear of the grain-spout, communicating with the central cavity of the axles, the said casting having lugs on the rear of the grain-spout, the whole being cast in one piece, substantially as described.

3. The combination, with a casting, having an axle on each side thereof, a draw-bar connection and a shield depending from the draw-bar connection, and provided with a grain-spout in front of the axles, the said parts being cast integral, of disks mounted upon the axles and behind the shield, substantially as described.

4. The combination with a casting having a hollow axle on each side thereof, and a grain-guide and a draw-bar connection in front of the axles and provided with a grain-spout in front of the axles and an oil-conduit, in the rear of the grain-spout, communicating with the central cavity of the axles, the said cast-

ing having lugs on the rear of the grain-spout, the whole being cast in one piece, of disks upon the axles, and a scraper adjustably secured between the disks upon the said lugs, 5 substantially as described.

5. The combination with a casting, having a hollow axle on each side thereof and a draw-bar connection, a shield and a grain-guide in front of the axles, and provided with a grain-spout between the axles and grain-guide, and with an oil-conduit in rear of the grain-guide, communicating with the cavity of the axles, and having lugs on the rear of the said oil-conduit, of disks mounted upon the said axles 10 in the rear of the said shield, and a plurality of scrapers adjustably mounted in relation to each other and to the axles, upon the said lugs and between the disks, substantially as described.
- 15 6. The combination with diverging axles, of disks mounted thereon, and having the inner sides of their edges beveled, and two scrapers, mounted between the disks and adjustable in relation to each other, the one scraper cleaning 20 the plane surfaces of the disks and the other

scraper cleaning the beveled surfaces thereof, substantially as described.

7. The combination with disks, of pivoted levers *s s*, scrapers *q q* pivoted to one end of the said levers, and a spring connecting the 30 opposite ends of the said levers, whereby the scrapers are forced against the disks and accommodate themselves to the inclination thereof, substantially as described.

8. The combination with hollow axles, serving as an oil-reservoir, of disks provided with hubs, mounted upon the said axles, means for retaining the hubs in place, and screw-threaded caps upon the hubs forming auxiliary oil-chambers upon the exterior of the axles, the 35 40 said auxiliary chambers being in communication with the said oil-reservoir in the interior of the axles, substantially as described.

Dated at Hamilton, Ontario, this 10th day of March, 1897.
